Augustus J. Gayley of Boston Massachusetts
Letters Patent

The schedule referred to in these Letters Patent and making part of the same containing a description in the words of the said Augustus J. Gayley himself of his improvement in the Steam Engine.

I, Augustus J. Gayley of Boston in the County of Suffolk and State of Massachusetts machinist and inventor, Do it known that I the said Augustus J. Gayley have invented constructed and applied to my new and useful improvement in the Steam Engine, which improvement is the principle thereof, and mode in which I have contemplated the application together with the manner of using the same I have herunto set forth and described as follows. Plates 1 & 2 represent different views of my improved Steam Engine. Fig 1, being a side elevation showing the several parts as they are arranged and combined together or connected with the frame. Fig 2. is an end elevation exhibiting the form and shape of the frame together with the cylinder while vibrating on its shaft or axis. The main part of my improvement and what I consider as new is affording the Steam cylinder A on the end of a long hollow shaft or mandrel B, suspended in bearings, near its extremity as seen in the drawings while other vibrating cylinders have generally been hung on the shaft journal or arms, projecting from the opposite sides of the circumference, and receding and moving in bearings connected to the frame work of the Engine, in which case the steam has usually entered through one arm, and departed through the other, so has been otherwise properly constructed to insure the necessary movement of the Engine. The operation of the engine may be described thus. The steam entering the induction pipe C being turned gives an impulsion to the steam from the boiler, which passing through the openings of the throttle valve D, is shot downwards into the pipe E (leading from the box C and situated in the hollow mandrel or shaft B) and thence into the steam valve chest F. From the valve chest it passes through

2.

The pipe f into the cylinder where it acts on the piston and forces it down wards. In the mean time a communication is opened by the valve passing by the slot in opening b , so that the steam or air under the piston escapes through the pipe g under the valve into the opening b . Then it through the slot f into the gland h from whence it escapes through the extraction pipe h . The construction of the valve and apertures b, c, m , are more clearly shown in Figs 2 & 3 (Plate 3.) The valve being stationary and attached to the end of a rod at the other end of which is secured to the lower part of the steam box c . The steam chest is divided by a partition m into two apartments, one for the reception of steam from the boiler, the other for it after leaving the cylinder. The head of the piston rod is immediately connected to the crank k on the main shaft o . h is the fly wheel, i a pulley or drum for communicating power to any machinery to which the Engine may be attached, j is the eccentric arming the plunger of the force pump n . l is the governor operated upon by a bevelled pinion on the end of the main shaft connected with a bevelled wheel on the upright shaft o . m, m , are iron ties with studs, screws and nuts for connecting the ends of the frame together. p is a counterpoise of the governor. The remainder of the machinery is constructed as represented in the drawings and may be otherwise placed or arranged if necessary.

In continuation of what I claim as my invention and improvement is the combination of the several parts together as described and exhibited in the annexed drawings, and separately I claim connecting a steam cylinder to the end of a long mandrel or shaft to shake back and forth and operate as I have herein mentioned. In testimony that the above is a true specification of my said invention and improvements I have hereunto set my hand this nineteenth day of March in the year of our Lord Eighteen hundred & thirty six.
